(57) **CLAIM**

The ornamental design for a sofa table with two-level top, as shown and described.

DESCRIPTION

FIG. 1 is a perspective view of a sofa table with two-level top showing my new design. The sofa, pillows, cushions, stools and ottoman, shown in broken line, do not form part of my design.

FIG. 2 is a top plan view thereof. The sofa, pillows, cushions, stools and ottoman, shown in broken line, do not form part of my design.

FIG. 3 is a rear elevational view thereof. The sofa and stools, shown in broken line, do not form part of my design.

FIG. 4 is a front elevational view thereof. The sofa, pillows, cushions, and ottoman, shown in broken line, do not form part of my design.

FIG. 5 is a left side elevational view thereof, the right side being a mirror image. The sofa, pillows, cushions, stools and ottoman, shown in broken line, do not form part of my design.

FIG. 6 is a front elevational view thereof, without the unclaimed environment.

FIG. 7 is a right side elevational view thereof, the left side being a mirror image.

FIG. 8 is a top plan view thereof.

FIG. 9 is a rear elevational view thereof.

FIG. 10 is a front perspective thereof.

FIG. 11 is a rear perspective thereof.

FIG. 12 is a front elevational view of another embodiment of a sofa table with two-level top of my new design.

FIG. 13 is a rear elevational view thereof.

FIG. 14 is a top plan view thereof; and,

FIG. 15 is a right side elevational view, the left side elevation being a mirror image.
